BLIND STITCH SEWING MACHINE

Charles W. Mueller, St. Louis, Mo., assignor to
 Lewis Invisible Stitch Machine Company, St.
 Louis, Mo., a corporation of Maine

Application April 10, 1933, Serial No. 665,423

16 Claims. (Cl. 112—178)

This invention relates to new and useful improvements in sewing machines generally, although particularly to machines for blind stitching hems along the bottoms of skirts and other articles of wearing apparel.

In blind stitch sewing machines as heretofore constructed for performing hemming operations, the hem and the adjacent portion of the body fabric are elevated by the ridge forming device 10 immediately prior to each needle penetrating stroke whereby the needle first enters the body fabric and then the hem, the hem thus receiving the thrust of the needle. When performing this hemming operation on light weight fabrics, the 15 hem lacks sufficient rigidity to properly resist the needle penetration and consequently the needle may either fail at times to enter the hem or at other times enter the hem at different distances from the hem fold, thereby creating an 20 irregular line of stitches.

Among the objects of this invention are to provide a blind stitch sewing machine having a hemmer and provided with means for supporting the hem against the thrust of the needle whereby 25 the latter will with certainty enter the hem at the same points relative to the hem fold during each penetrating stroke of the needle; to provide a yieldable hem supporting means whereby a hem having a cross seam therein may be fed past the 30 needle and properly supported during said passage against the thrust of the needle; to provide such a supporting means with a manually operable device for moving said supporting means laterally against the tension of the yieldable 35 means to accommodate the machine to different weights of materials; and to provide such a supporting means which is simple in construction and is easily attached to the stationary presser foot of the machine.

With these and other objects in view which will more fully appear, the nature of the invention will be more clearly understood by following the description, the appended claims, and the several views illustrated in the accompanying drawings.

40 In the drawings:—

Figure 1 is an end elevation of a blind stitch sewing machine equipped with my invention.

Figure 2 is a horizontal view taken directly above the stationary presser foot.

Figure 3 is a top plan view of the presser foot, Figure 4 is a bottom plan view thereof.

Figure 5 is a transverse sectional view taken on the line 5—5 of Figure 3.

Figure 6 is a detail view partly in front elevation and partly in section showing the relation

between the presser foot, the needle, the ridge forming device, the hemmed fabric, the work clamp, the feed dog, and the hem supporting means, and

Figure 7 is a perspective view of the hem supporting means.

Like reference numerals designate corresponding parts throughout the several figures of the drawings.

Referring to the accompanying drawings, I have shown my invention applied to a "Lewis" blind stitch sewing machine which includes a stitching head A and a work arm B such as is shown in my co-pending application Ser. No. 594,930, filed Feb. 24, 1932.

Rigidly attached to the lower end of the stitching head A is a presser foot 5 which is provided centrally with a slot or opening 6 extending rearwardly from the front edge 7 thereof. The foot is also provided directly in rear of the opening 6 with a feed slot 8 which is divided from said opening by a bridge 9 having a longitudinal groove 10 in its under face.

As previously stated, my invention is adapted to form a hem in the body fabric and blind stitch said hem to the body fabric. In the present instance, I have disclosed a single thread stitch forming mechanism for blind stitching hems; but I wish it to be understood that any other stitch forming mechanism may be employed if desired.

In the present instance, the single thread stitch forming mechanism includes a curved needle 11 which is fixed to an oscillatory needle arm 12 mounted on the stitching head and driven from the main shaft of the machine in the usual manner. The needle 11 has its penetrating movement across the line of feed of the fabric and in a plane directly above the opening 6 of the foot. Cooperating with the needle to form a line of single thread chain stitches is a looper 13 which is mounted on the stitching head A and has its movements imparted thereto from the main shaft of the machine through the usual driving connections. Disposed above and supported on the work arm B is a flat work plate 14. A hemmer 15 is rigidly although adjustably mounted on the work plate 14 at a point in front of the presser foot 5, the nose of the hemmer projecting rearwardly and having its delivery end located immediately in front of the opening 6 of the foot.

Disposed below the presser foot and cooperating therewith is a work presenting mechanism which includes the usual vertically reciprocating work clamp 16, a 4-motion feed dog 17, and a vertically reciprocating ridge forming element 18.

all being of the usual construction and operated in the manner described in my co-pending application referred to above. It will be noted that the ridge forming element or plunger 18 operates in the presser foot opening 6 immediately under the path of needle travel and that the main feed dog 17 engages the body fabric and feeds the same rearwardly from the hemmer 15 past the ridge forming element 18 and needle 11. It will also be observed, as shown particularly in Figure 6, that the ridge forming element 18 elevates the hem 19 and the adjacent portion of the body fabric 20 into needle penetrating position whereby the needle will first enter the body fabric and then the hem.

In order to support the hem 19 against the thrust of the needle 11, I have provided the presser foot 5 with a supporting finger or wall 21 which is mounted on an arm 22 pivoted by a screw 23 to the under face of the presser foot 5 at a point in rear of the finger so as to permit said wall or finger 21 to be moved back and forth across the opening 6 of the foot. The finger 21 is thus located in the presser foot opening 6 on the side 25 of the ridge forming element 18 opposite the point of needle penetration in the hem, and is provided in its side face adjacent the ridge forming element with a hem-receiving groove 21^a. A flat spring 24 is attached by a screw 25 to the adjacent side of the foot and the free end of this spring engages in a slot 26 formed in the arm 22 and functions to yieldably urge the finger or wall 21 toward the ridge forming element 18. In order to positively adjust the finger in the opposite direction to accommodate materials of 30 different weights, I have provided the arm 22 with an upstanding lug 27 which is located at one side of the foot and is provided with a threaded opening 28 for receiving an adjusting screw 29 which cooperates with the adjacent side wall of the foot to swing the finger or wall 21 outwardly 35 against the tension of the spring 24.

In operation the fabric 20 is fed through the sewing machine in the usual manner and a hem 19 is formed in the fabric by the hemmer 15. This hem passes to the right of the ridge forming element or plunger 18, and as shown in Figure 6 the plunger intermittently elevates the hem and the adjacent portion of the body fabric whereby the same is formed into a ridge which is entered by the needle 11, the latter first entering the body fabric and then the hem. When the needle penetrates the hem, the latter is supported against the thrust of the needle by the finger or wall 21, and by means of the spring 24 the finger yields laterally whenever a cross seam in the body fabric is fed past said finger. By means of the adjusting screw 29 the position of the finger 21 may be adjusted to accommodate fabrics having different weights and thicknesses. It will furthermore be observed that the yieldable finger 21 is normally urged toward the ridge forming element 18 and consequently the hem 19 is firmly clamped between the finger and the element during the penetrating stroke of the needle.

It is of course to be understood that the details of structure and arrangement of parts may be variously changed and modified without departing from the spirit and scope of my invention.

I claim:—

1. In a blind stitch sewing machine, the combination with a stationary presser foot having an opening extending rearwardly from the front edge thereof for receiving a ridge of material,

of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, and means located in the opening of the foot on the side of the ridge forming element opposite the point of needle penetration in the hem to support the latter against the thrust of the needle.

2. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, a finger movably located in the presser foot opening on the side of the ridge forming element opposite the point of needle penetration in the hem to support the latter against the thrust of the needle, and a spring for normally urging the finger toward the ridge forming element.

3. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, a finger movably located in the presser foot opening on the side of the ridge forming element opposite the point of needle penetration in the hem to support the latter against the thrust of the needle, a spring for normally urging the finger toward the ridge forming element, and manually adjustable stop means to variably limit the movement of the finger toward said ridge forming element.

4. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the

foot and having its delivery nose located immediately in front of said opening, a ridge forming element for projecting a ridge of hemmed material upwardly through the opening in the foot and into the path of movement of the needle whereby the needle will first enter the body fabric and then the hem, and a finger mounted on the presser foot and located in the opening thereof on the side of the ridge forming element opposite the point of needle penetration in the hem to support the latter against the thrust of the needle.

5 10 15 20 25 30 35 40 45 50 55 60 65 70 75

5. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, and a finger mounted on the presser foot and located in the opening thereof on the side of the ridge forming element opposite the point of needle penetration in the hem to support the latter against the thrust of the needle, said finger being laterally adjustable toward and from the hem to accommodate hems of different thicknesses.

6. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, a finger mounted on the foot and located in the opening thereof on the side of the ridge forming element opposite the point of needle penetration in the hem to support the latter against the thrust of the needle, and a spring mounted on the foot and cooperating with the finger to yieldably retain the latter in one extreme position of movement.

7. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric

and then the hem, a finger mounted on the foot and located in the opening thereof on the side of the ridge forming element opposite the point of needle penetration in the hem to support the latter against the thrust of the needle, a spring mounted on the foot and cooperating with the finger to yieldably retain the latter in one extreme position of movement, and means for positively adjusting the finger in the opposite direction and against the tension of said spring.

8. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, a finger located in the opening of the presser foot on the side of the ridge forming element opposite the point of needle penetration in the hem, an arm pivotally mounted on the foot in rear of the finger and rigidly connected to the latter, and a spring mounted on the foot and cooperating with the arm for normally urging the finger toward the ridge forming element.

9. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material upwardly through the opening in the foot and into the path of movement of the needle whereby the needle will first enter the body fabric and then the hem, a finger located in the opening of the presser foot on the side of the ridge forming element opposite the point of needle penetration in the hem, an arm pivotally mounted on the foot in rear of the finger and rigidly connected to the latter, a spring mounted on the foot and cooperating with the arm for normally urging the finger toward the ridge forming element, and means for positively adjusting the finger in the opposite direction and against the tension of said spring.

10 15 20 25 30 35 40 45 50 55 60 65 70 75

10. In a blind stitch sewing machine, the combination with a stationary presser foot having an opening extending rearwardly from the front edge thereof for receiving a ridge of material, of a feeding means cooperating with the foot to feed the material rearwardly, a stitch forming mechanism including a reciprocatory needle disposed above the opening in the foot and having its penetrating stroke extending in a plane across said opening, a hemmer disposed in front of the foot and having its delivery nose located immediately in front of said opening, a ridge forming element for projecting a ridge of hemmed material up-

wardly through the opening in the foot and into the path of movement of the needle whereby the needle will first enter the body fabric and then the hem, a finger located in the opening of the 5 presser foot on the side of the ridge forming element opposite the point of needle penetration in the hem, an arm located below and pivotally mounted on the foot in rear of the finger and rigidly connected to the latter, a lug extending 10 upwardly from the arm at one side of the foot, a spring mounted on the foot and cooperating with the arm for normally urging the finger toward the ridge forming element, and an adjusting screw mounted in the lug for cooperation with 15 the side of the foot for positively adjusting the finger against the tension of the spring.

11. In a blind stitch sewing machine, the combination with a stationary presser foot having an opening extending rearwardly from the front 20 edge thereof for receiving a ridge of material, of a feeding means cooperating with the foot to feed the material rearwardly, a stitch forming mechanism including a reciprocating needle disposed above the opening in the foot and having its penetrating stroke extending in a plane across said opening, a hemmer disposed in front of the foot and having its delivery nose located immediately in front of said opening, a ridge forming element 25 for projecting a ridge of hemmed material upwardly through the opening in the foot and into the path of movement of the needle whereby the needle will first enter the body fabric and then the hem, a finger movably located in the presser foot opening on the side of the ridge forming element 30 opposite the point of needle penetration in the hem to support the latter against the thrust of the needle, the side of the finger adjacent the ridge forming element being formed with a rearwardly extending hem-receiving groove, and a spring 35 for normally urging the finger toward the ridge forming element.

12. A presser foot for blind stitch sewing machines having an opening extending rearwardly from its front edge for receiving a ridge of material, a finger movably mounted on the presser foot and located at one side of said opening, and a spring for normally urging the finger toward the other side of the opening.

13. A presser foot for blind stitch sewing machines having an opening extending rearwardly from its front edge for receiving a ridge of material, a finger movably mounted on the presser foot and located at one side of said opening, a spring for normally urging the finger toward the other side of the opening, and manually adjustable stop means to variably limit the movement of the finger toward said other side of the opening.

14. A presser foot for blind stitch sewing machines having an opening extending rearwardly from its front edge for receiving a ridge of material, a finger movably mounted on the presser foot and located at one side of said opening, an arm pivotally mounted on the foot in rear of the finger and rigidly connected to the latter, and a spring mounted on the foot and cooperating with the arm for normally urging the finger toward the other side of the opening.

15. A presser foot for blind stitch sewing machines having an opening extending rearwardly from its front edge for receiving a ridge of material, a finger movably mounted on the presser foot and located at one side of said opening, an arm pivotally mounted on the foot in rear of the finger and rigidly connected to the latter, a spring mounted on the foot and cooperating with the arm for normally urging the finger toward the other side of the opening, and means for positively adjusting the finger in the opposite direction and against the tension of said spring.

16. A presser foot for blind stitch sewing machines having an opening extending rearwardly from its front edge for receiving a ridge of material, a finger movably mounted on the presser foot and located at one side of said opening, an arm pivotally mounted on the foot in rear of the finger and rigidly connected to the latter, a spring mounted on the foot and cooperating with the arm for normally urging the finger toward the other side of the opening, and means for positively adjusting the finger in the opposite direction and against the tension of said spring, said adjusting means comprising a screw mounted in the arm for cooperation with the side of the foot.

CHARLES W. MUELLER.
